H. H. SCHROYER.

WEATHER STRIP.

APPLICATION FILED SEPT. 1, 1911.

1,087,146.

Patented Feb. 17, 1914

UNITED STATES PATENT OFFICE.

HARRY H. SCHROYER, OF CHICAGO, ILLINOIS, ASSIGNOR TO THE ACME SUPPLY COMPANY, A CORPORATION OF ILLINOIS.

WEATHER-STRIP.

1,087,146.

Specification of Letters Patent. Patented Feb. 17, 1914.

Application filed September 1, 1911. Serial No. 647,205.

To all whom it may concern:

Be it known that I, HARRY H. SCHROYER, a citizen of the United States, and a resident of the city of Chicago, in the county of Cook 5 and State of Illinois, have invented certain new and useful Improvements in Weather-Strips; and I do hereby declare that the following is a full, clear, and exact description of the same, reference being had to the accompanying drawings, and to the numbers of reference marked thereon, which form a part of this specification.

This invention relates to new and useful improvements in weather strips, and although applicable for general use, is shown more particularly embodied as a weather strip or guard for car windows.

It is an important object of this invention to provide a weather strip adapted to prevent air or dust from entering between the upper and lower sashes of the window or between the sash frame or parting strip.

It is also an object of this invention to provide a weather strip adapted to afford 25 a guide for the sliding sash of a window.

It is a further object of the invention to provide a weather strip adapted to prevent the rattling of the sashes in the frame.

It is finally an important object of this 30 invention to provide a simple, durable and inexpensive weather strip adapted to effectively seal the window and prevent the rattling of the sash.

The invention consists in the matters hereinafter described and more fully pointed out and defined in the appended claims.

In the drawings: Figure 1 is a fragmentary horizontal section taken through the frame and the upper rail of the lower sash, 40 showing the device embodying my invention applied to a car window. Fig. 2 is a fragmentary face view of the strip adapted to be secured to one of the rails of a sash. Fig. 3 is a transverse section of the upper 45 rail of the lower sash and the lower rail of the upper sash with the strip shown in Fig. 2, conveniently installed. Fig. 4 is a fragmentary sectional view similar to that shown in Fig. 1, and illustrating a slightly 50 modified arrangement of the weather strip or guard.

As shown in the drawings: 1, indicates the sill of the window; 2, the inner sill or base;

3, the lamb; 4, the outer stop; 5, the inner stop, and 5^a, the inner curtain stop, which 55 are of the usual construction.

As shown in Figs. 1 and 4, one of the strips embodying my invention comprises an approximately rectangular portion 6, adapted to be secured to the inner stop 5, in any 60 suitable manner, and completely incase the exposed surfaces of the same, and provided with a flange 7, which extends outwardly to a point approximately midway between the upper and lower sashes and then is turned 65 inwardly toward the center of the window and then back upon itself to afford a parting bead or strip 8. Slidably engaged between the inner stop 5, and the parting strip 8, is the lower sash 9, having a resilient 70 strip secured on the side rails thereof adapted to bear against the parting strip 8. As shown, said resilient strip comprises a web 10, adapted to be rigidly secured to the sash in any suitable manner, and a resilient, 75 laterally offset portion 11, adapted to normally bear against the parting strip 8, to effectually prevent the inlet of air between the stiles of the sash and the jambs 3.

The lower rail of the upper sash is chamfered or cut away at each end on its inner side to afford clearance for the parting strip and a horizontal groove extends for the entire length of said lower rail, as shown in Figs. 1 and 3. Rigidly secured in said 85 groove is a sealing strip comprising a relatively flat strip of metal 12, having the lateral edges 12^a, thereof flanged to afford a channel with slightly inturned edges to receive and firmly secure suitable packing material. For this purpose a narrow strip of Brussels carpet 13, or other suitable material (preferably having a nap) is engaged in said channel with the nap firmly bearing 90 against the parting strip 8, resilient strip 11, 95 and the upper rail of the lower sash to force the same inwardly against the portion 6, on the inner stop 5. This prevents rattling and effectually seals the space between the lower rail of the upper sash and the upper rail of 100 the lower sash, to prevent the admission of wind, dust and rain.

The construction disclosed in Fig. 4, is practically identical with that shown in Fig. 1, except that the side rails of the lower sash 105 are rabbeded on the outer side as indicated

by 14, to receive that part of the parting bead or strip 8. As shown also in this construction, the resilient strip or plate 15, is flat and bears against the parting strip 8, to seal the sides of the sash as before. Owing to the fact that the parting strip is contained in the rabbet 14, it is not necessary to chamfer or rabbet the lower rail of the upper sash as in the construction disclosed in Fig. 1. The sealing strip (which is similar to that disclosed in Fig. 1) is secured to said lower rail in any suitable manner and bears against the upper rail of the lower sash to hold the same firmly against the portion 6, secured to the inside stops.

The operation is obvious from the construction described. In installing the device, as shown in Fig. 1, that part of the weather strip which affords the parting strip 8, is positioned outside of the inner sash and the outer sash is provided with a recess to receive the strip 12, to permit the same to bear with equal pressure upon the parting strip, resilient strip and the lower rail of the sash.

In the construction shown in Fig. 4, the installation of the respective elements is practically the same as that disclosed in Fig. 1, with the exception that in this construction the stile of the window is provided with a recess to receive the parting strip, thereby obviating the necessity of providing recesses in the ends of the lower rail of the upper sash to insure even pressure of the strip 12, upon the parting strip, resilient strip and the lower rail of the upper sash.

Of course, details of construction may be varied without departing from the principles of this invention, and I therefore do not purpose limiting the patent to be granted upon this application otherwise than necessitated by the prior art.

I claim as my invention:

1. A device for window sashes of the class described, comprising in combination inter-fitting weather strip members loosely engaged with each other when one of the sashes is open, and a yielding sealing member adapted to thrust said weather strip members into close engagement with one another when the sashes are closed. 45

2. A device for window sashes of the class described, comprising in combination co-acting resilient weather strip members adapted loosely to engage one another when one of the sashes is open, and a strip of yielding packing material secured on the meeting rail of one sash to bear against the meeting rail of the other sash when both sashes are closed, thereby sealing the meeting rails and forcing 60 the weather strip members into tight engagement with one another. 55

3. A device of the class described, comprising in combination a strip of metal bent to afford a double channel, an integral resilient tongue extending outwardly from the wall of one of said channels, a cover plate adapted to bear against said tongue when said plate and strip are attached to a window sash and frame respectively, and a strip 65 of yielding packing secured to the meeting rail of one sash and adapted to bear against the meeting rail of the other sash to force said sashes apart and to force the cover plate and resilient tongue into close engagement with each other when said sashes are closed. 70

In testimony whereof I have hereunto subscribed my name in the presence of two subscribing witnesses.

HARRY H. SCHROYER.
